Inventor

William M. Gilson,

C. A. Snow & Co.

UNITED STATES PATENT OFFICE.

WILLIAM M. GILSON, OF BLANCHARD, IOWA.

PHOTOGRAPHIC HEAD AND BODY REST.

SPECIFICATION forming part of Letters Patent No. 527,056, dated October 9, 1894.

Application filed December 9, 1893. Serial No. 493,198. (No model.)

To all whom it may concern:

Be it known that I, WILLIAM M. GILSON, a citizen of the United States, residing at Blanchard, in the county of Page and State 5 of Iowa, have invented a new and useful Photographic Head and Body Rest, of which the following is a specification.

My invention relates to improvements in photographic head-rests, the objects in view 10 being to produce a cheap and simple device that may be conveniently operated and adjusted so as to support in any desired position against movement the head and body of an infant, small child, or grown person, so as 15 to insure a perfect picture and obviate any blurring thereof.

Various other objects and advantages of the invention will appear in the following description and the novel features thereof will be particularly pointed out in the claims.

Referring to the drawings:—Figure 1 is a perspective view of a head-rest embodying my invention. Fig. 2 is a longitudinal sectional view through the main standard. Fig. 25 3 is a transverse sectional view through the joint of the head-rest. Fig. 4 is a similar view through the joint of the body-rest.

Like numerals of reference indicate like parts in all the figures of the drawings.

30 In practicing my invention I prefer to secure the device hereinafter described to a seat, though if desired it may be applied to a stand that is usually employed. In the present instance, however, I secure to the under side 35 and back of a seat a loop or keeper 1, in which I locate a binding-screw 2 and adjust by means of said binding-screw in a horizontal manner to and from the seat, an arm 3, at whose outer end I locate a T-shaped coupling 4. In this coupling 4 a binding-screw 5 is located, and the same is designed to impinge upon and provide the means of adjustment of a vertical main standard 6, at whose upper end a cap 7 is secured. A disk 8 is 40 formed on one side of the cap and vertically disposed, said disk being centrally perforated, and a clamping-disk 9 is applied to the face of the disk 8 and similarly perforated. These two disks receive an eye-bolt 10, upon whose 45 threaded end a binding-nut 11 is arranged, and which is adapted to be seated or bound

against the stationary disk and thus draw the eye-bolt 10 within the movable disk 9.

A horizontal rest-arm 12 is adjustably arranged within the eye of the bolt 10 and may 55 be secured at any point of its horizontal or vertical adjustment by means of the aforesaid binding-nut 11. At the forward end of this rest-arm 12 a disk 13 is formed, the same being perforated to correspond with similar 60 perforations formed in a pair of curved body-embracing arms 14 of the ordinary construction, and through these perforations of the disk and body-embracing arms 14 a binding-screw 15 is passed. The device may be thus 65 employed for retaining in position the body of the child or grown person as desired, the embracing-arms 14 being adjustable relatively so as to conform to the size of the person and to support the body erect in the desired position and against any possible movement. I prefer, however, to also adapt the device for supporting the head of the person, and I will therefore proceed to describe an additional attachment.

70 Located upon the main standard 6 is a T-shaped coupling 16, the same being adjustable up and down upon said standard and secured at any point by a binding-screw 17. This T-coupling, by means of an intermediate 75 connection 18, is connected to a second or outer T-coupling 19, which carries a binding-screw 20 designed to impinge upon and serve as the means for securing in adjusted position a second vertical standard 21 which projects 80 above the first mentioned standard and is provided at its upper end with a T-head 22. The T-head 22 has a binding-screw 23 located in its upper end, and the same impinges upon and secures in any desired horizontal adjust- 85 able position a horizontal arm 24, which may be adjusted in and out above the arm 12. The outer end of this arm has formed thereon a perforated disk 25 and at opposite sides of this disk 25 are disks 26 which have their outer 90 faces inclined and are centrally perforated as shown. A screw 27 passes through the three disks and through the rear disk-like ends of the head-rest arms 29 and binding-nuts 30 are arranged on the extremities of the screw and 95 serve to clamp the disk-like ends of the arms upon the inclined disks.

As illustrated in Fig. 3 of the accompanying drawings, the disks 26 are provided with laterally extending circumferential flanges; and the inner terminals or disks of the arms 29 are concavo-convex, and bear against the outer edges of the flanges of the disks 26. By raising these arms the same are loosened by reason of the inclined faces of the disks, and by lowering them to embrace the head 10 they are tightened or brought together so as to form a suitable rest that is stable and against which the head may recline and be held.

The screw 27 is rigidly secured to the disk 25 by any suitable means; and the disks 26 are loosely arranged on the screw, and have their flat faces fitting against the disk 25. When the arms 29 are raised, the cam disks 26 will be pressed against the disk 25, and sufficient friction will be created to prevent the disks 26 from rotating with the arms.

From the foregoing description it will be seen that I have provided a very simple device, that is what might be termed universally adjustable and is thus adapted for holding the bodies as well as the heads of persons during photographing.

Having described my invention, what I claim is—

1. In a photographic head and body rest, the combination of a standard a horizontal arm supported by the standard and terminating at its front end in a centrally perforated disk, a transverse screw passing through the perforation of the disk and rigidly connected with the disk and having its opposite sides threaded, the disks 26 provided at their peripheries with laterally extending circumfer-

ential cam flanges, the head rest arms provided at their inner ends with concavo-convex disks centrally perforated to receive the screw and arranged thereon and fitting against the said cam flanges, and nuts arranged on the outer extremities of the screws and engaging the disks of said arms, substantially as described.

2. In a photographic head and body rest, the combination of a seat provided with a rearwardly offset vertically disposed socket, the main standard 6 vertically adjustable therein and carrying at its upper end the adjustable body supporting and embracing arms 14 extending over the rear of the seat, the vertical standard 21 rearwardly offset from the main standard 6 and adjustably connected therewith, the horizontal arm terminating at its front end in a centrally perforated disk, a transverse screw passing through the perforation of the disk and rigidly connected with the disk and having its opposite sides threaded, the disks 26 provided at their peripheries with laterally extending circumferential cam flanges, the head rest arms provided at their inner ends with concavo-convex disks centrally perforated to receive the screw and arranged thereon and fitting against the said cam flanges, and nuts arranged on the outer extremities of the screws and engaging the disks of said arms, substantially as described.

In testimony that I claim the foregoing as my own I have hereto affixed my signature in the presence of two witnesses.

WILLIAM M. GILSON.
